UNITED STATES PATENT OFFICE.

EDWARD L. HILDERBRAND, OF SULLIVAN, INDIANA.

AXLE-SPINDLE.

SPECIFICATION forming part of Letters Patent No. 624,805, dated May 9, 1899.

Application filed March 11, 1899. Serial No. 708,721. (No model.)

To all whom it may concern:

Be it known that I, EDWARD L. HILDERBRAND, a citizen of the United States, residing at Sullivan, in the county of Sullivan and 5 State of Indiana, have invented a new and useful Axle-Spindle, of which the following is a specification.

This invention relates to axle-spindles, and has for its object to provide a removable 10 skein with means for lubricating the inner end of the axle-box.

With this end in view the present invention consists in the combination and arrangement of parts, as will be hereinafter more 15 fully described, shown in the accompanying drawings, and particularly pointed out in the appended claim.

In the drawings, Figure 1 is a horizontal longitudinal sectional view showing the improvements applied to an axle. Fig. 2 is a transverse sectional view on the line xx , Fig. 1. Fig. 3 is a detail perspective view of the axle-skein.

Corresponding parts are designated by like 25 reference characters in all the figures of the drawings.

Referring to the accompanying drawings, 1 designates an ordinary spindle having the usual threaded outer extremity 2 and also 30 threaded at its inner end, as at 3.

The skein 4, which is illustrated in detail in Fig. 3, is internally threaded, as at 5, at its inner end. This latter end is enlarged and provided with an annular flange 6, which 35 overhangs the body of the skein and forms therewith an annular groove or pocket 7, surrounding the exterior of the threaded end of the skein. Extending longitudinally of the upper face of the skein is a groove 8, forming an oil chamber or reservoir, and branch 40 grooves 9 extend out from opposite sides of the reservoir. The branch grooves 10 at the flanged end of the skein extend into the pocket 7 to convey the lubricant into the same.

45 By reference to Fig. 1 particularly it will be seen that the skein is removably fitted to the spindle by means of the threaded connections 5 and 3, respectively. A suitable washer 11 is placed in the pocket 7 of the skein, and 50 the axle-box 12 is then slipped upon the skein. The inner end 13 of the box is fitted into the pocket 7, a washer 14 having been

previously fitted to the end of the box against the annular shoulder 15. The outer threaded end of the spindle is provided with the 55 usual hub-attaching nut 16. The groove 8 being in the top of the skein, which is fixed upon the spindle, a suitable lubricant is placed in the groove, and as the box is fixed to the hub by means of the wings 17 in the common 60 manner the box turns upon the skein and the lubricant is fed automatically through the branch grooves 9 to the interior of the box. The branch grooves 10 lead into the pocket 7, and thereby convey the lubricant to the inner 65 end of the axle-box, which turns within the pocket.

The present construction provides an exceedingly simple and efficient device, as the skein can be readily replaced when worn and 70 the lubricant is fed directly to the parts needing the same. The flange 6, overhanging the inner end of the box and abutting against the shoulder of the same, prevents sand and dirt 75 from having access to the bearing-surface of the box and skein.

Changes in the form, proportion, size, and the minor details of construction within the scope of the appended claim may be resorted to without departing from the spirit or sacrificing any of the advantages of this invention. 80

Having thus described the invention, what is claimed is—

The combination with an axle-spindle, of a skein having an exterior annular flange at 85 its inner end overhanging the body of the skein and forming therewith an exterior pocket, the upper exterior face of the skein having an oil-chamber provided therein and branch grooves leading therefrom, some of 90 the grooves leading into the annular pocket, and an axle-box having its inner end seated within the annular pocket of the skein, the grooves leading into the pocket forming means whereby the inner end of the box may 95 be lubricated, substantially as shown and described.

In testimony that I claim the foregoing as my own I have hereto affixed my signature in the presence of two witnesses.

EDWARD L. HILDERBRAND.
